UNITED STATES PATENT OFFICE.

THOMAS W. CARTER, OF WEST MERIDEN, CONNECTICUT.

DESIGN FOR A THREAD-HOLDER.

Specification forming part of Design No. **6,244**, dated November 12, 1872.

To all whom it may concern:

Be it known that I, THOMAS WALTER CARTER, of West Meriden, in the county of New Haven and State of Connecticut, have invented a new Design for Thread-Holder; and I do hereby declare the following, when taken in connection with the accompanying photographic illustration and the letters of reference marked thereon, to be a full, clear, and exact description of the same, and which said illustration constitutes part of this specification and represents a perspective view.

This invention relates to a design for apparatus for holding several spools of thread; and it consists in the peculiar configuration of the holder, as more fully hereinafter described, and shown in the accompanying illustration.

From a base a center post rises, surmount-

ed by a figure of Cupid with arms upraised, holding a wreath over his head, upon which a pin-cushion is placed. Near the base, and at a short distance above, are arranged a pair of plates formed of tracery, with several projecting points, through which a spindle to support the spools is set, the spindle passing through the spools between the plates, all as shown in the accompanying illustration.

I claim as my invention—

The design for thread-holder as described, and shown in the accompanying illustration.

THOMAS WALTER CARTER.
